UNITED STATES PATENT OFFICE.

JAMES W. CAIN, OF DETROIT, MICHIGAN.

SPOTLIGHT SIGNAL.

1,413,096.

Specification of Letters Patent. Patented Apr. 18, 1922.

Application filed December 17, 1921. Serial No. 523,127.

To all whom it may concern:

Be it known that I, JAMES W. CAIN, a citizen of the United States, residing at Detroit, in the county of Wayne and State of Michigan, have invented a new and useful Spotlight Signal, of which the following is a specification.

This invention relates to signaling devices especially constructed for use in connection with motor vehicles, the primary object of the invention being to provide a signal which may be clearly visible in the daylight as well as in the dark.

Another object of the invention is to provide a novel lamp construction to insure a true contact between the lamp and its socket, to improve the operation of the lamp.

With the foregoing and other objects in view which will appear as the description proceeds, the invention resides in the combination and arrangement of parts, and in the details of construction hereinafter described and claimed, it being understood that changes within the scope of what is claimed, may be made without departing from the spirit of the invention.

Referring to the drawing:

Figure 1 is a sectional view through a lamp forming a part of a signaling device constructed in accordance with the present invention, and showing the same as secured to a mud guard.

Figure 2 is a front elevational view of the lamp.

Figure 3 is an enlarged detail view of the connection between the lamp and its socket.

Figure 4 is a detail view of the contact member.

Referring to the drawing in detail, the device is shown as secured to a mud guard of a vehicle, the mud guard being indicated at 5. A bracket member indicated at 6 has connection with the mud guard 5, as by means of the bolts 7, it being understood however that the construction of the bracket may be changed to meet various requirements.

The lamp casing embodies a circular body portion 8 having a threaded portion 9 and a rear curved reflecting wall 10, the rear curved reflecting wall being formed with a threaded extension 11 terminating in an inwardly extending circular flange 12. This circular flange 12 provides a seat for the insulating collar 13, which is held against the flange 12 as by means of the socket member

14 that is also formed with a threaded portion, as clearly shown by Figure 1 of the drawing.

The socket member includes an inwardly extending threaded socket 15 designed to accommodate the lamp base 16, the inner end of the socket 15 being formed with an inwardly extending flange 17 to restrict movement of the lamp 16 within its socket member and prevent the lamp from moving the contact member to an inactive position, upon the insertion of a lamp.

Positioned within the socket member 14 is a tubular housing 18 which supports the contact block 19 that carries the contact member 20, forming an important feature of the invention. This contact member is formed preferably of a strip of flexible metal having an opening 21 and a contact head 22, it being understood that the length of metal is bent intermediate its ends to bring the ends thereof to positions in spaced relation with each other. The opening formed in one end of the contact member is designed to accommodate the securing screw 23, whereby the contact block may act as the support for the contact members 20. Thus it will be seen that the opposite end of the contact member lies in a position to be engaged by the contact member of the lamp bulb positioned in the socket.

A cover indicated at 24 forms a part of the lamp housing and is formed with a threaded portion to be received by the threaded portion 9 of the lamp casing, whereby the cover may be removably secured to the lamp housing. The cover is formed with suitable letters or numbers, by cutting away portions of the cover as shown by Figure 2 of the drawings. Positioned at the rear of the cover is a transparent member 25 suitably colored to indicate danger.

The lamp may be in circuit with any suitable source of electric supply and may be controlled by a suitable switch member, not shown.

Having thus described the invention, what is claimed as new is:

1. A signaling lamp including a body portion having a rearwardly extending portion provided with a flange, an insulating collar contacting with the flange, a socket member threaded within the rearwardly extending portion and contacting with the socket member to secure the insulating collar against

- movement, a socket forming a part of the socket member, a contact block positioned within the socket member and carrying a contact member, said contact member being formed of a strip of flexible material bent upon itself, a lamp positioned within the socket member and adapted to engage the contact member, and a cover for the body portion.
10. 2. A signaling lamp including a body portion having a rearwardly extending portion provided with a flange, an insulating collar engaging the flange, a socket member positioned within the rearwardly extending portion, and contacting with the insulating collar, a socket forming a part of the socket member and having an inwardly extending flange, a lamp positioned within the socket and adapted to engage the inwardly extending flange of the socket to restrict movement thereof, means within the socket member for completing a circuit to the lamp, and a removable cover for the body portion. 20
15. In testimony that I claim the foregoing as my own, I have hereto affixed my signature in the presence of two witnesses. 25

JAMES W. CAIN.
